UNITED STATES PATENT OFFICE.

JOEL B. PRATT, OF CORNING, NEW YORK.

IMPROVEMENT IN KNIFE-SHARPENERS.

Specification forming part of Letters Patent No. **56,264**, dated July 10, 1866.

To all whom it may concern:

Be it known that I, JOEL B. PRATT, of Corning, in the county of Steuben and State of New York, have invented a new and Improved Knife-Sharpener; and I do declare that the following is a full and exact description thereof, viz:

A wooden or iron frame, *a*, upon which rests the axle of a bevel-wheel, *b*, and from which block *a* two upright metallic posts or standards, *c*, protrude, and the cast-steel bevel-wheel *d* upon the axle *b*, between the said posts, of such size that it will lap upon each post,

the sharp or bevel edge touching the post; or two wheels may be used with one post.

What I claim as new is—

The arrangement of the wheel with the standards, the bevel-wheel resting by its axle on a wooden frame and lapping two upright metallic posts, all arranged and combined as herein set forth.

J. B. PRATT.
